Attorney

UNITED STATES PATENT OFFICE

RICHARD LINN LLOYD, OF PROVIDENCE, RHODE ISLAND

TENPIN HOUSING

Application filed April 5, 1929. Serial No. 352,823.

This invention relates to improvements in pin setting devices adapted for use in connection with the game of bowling or the like.

The prime object of this invention is to provide an improved means for quickly and efficiently returning the pin to its housing after the pin has been released from magnetic contact and connection with the alley of the game.

10 A further object of this invention is to provide a housing for the pin on its release from the alley having therein resilient means mounted on a spindle for actuating a pulley having wound thereon a cable of wire or 15 otherwise for raising the pin.

Other objects of this invention will appear from the following detailed description of the device and as disclosed in the single sheet of drawings which is herewith made a part 20 of this application.

In the drawings:

Figure 1 illustrates a vertical elevational view of the housing and the pin spaced from each other under tension, the pin being held 25 on the alley by magnetic attraction and against the potential energy of a spring wound on a spindle within the housing.

Figure 2 illustrates a vertical sectional view of the housing, disclosing the pin in 30 raised position therein.

Figure 3 represents a sectional view of the Figure 2 taken along line 3—3.

Figure 4 represents a sectional view of the upper portion of the housing, disclosing the spindle for supporting the pulley and spring, the spring being disclosed under tension as it 35 would be in case of the pin being in position on the alley.

It has been found from experience that the 40 resilient or spring members usually connecting the pins to the upper inside portion of the housings become weakened through use and are otherwise objectionable, particularly for service in connection with the larger 45 games of bowling, where the pins and balls are quite large and heavy. The object, therefore, of this invention is to provide a more positive means for returning the pins to the housing than that now in common use, and as 50 one modification of the invention, it is pre-

ferred that Number 1 designate the main body portion of the housing which may be made of any suitable material such as metal, and provided at its lower or open end with an internally threaded portion 2 for the purpose of receiving in cooperative relationship a clamping element 3 adapted to clamp the housing 1 in firm and fixed relationship to a plate member 4 which by some means not shown is adapted to be lowered or raised as 55 may be desired in order to set the pin 5 in playing position upon the alley 6, the pin 5 being detachably held in position on the alley 6 by means of magnetic attraction or other suitable device. A cable member 7 made of wire or other suitable material is preferred to be attached to the upper end of the pin member 5 by means of an eye element 8 securely screwed or fastened into the pin as disclosed at 9, the eye portion 8 being preferably positioned within a groove 10. It is to be 60 understood that other fastening means may be used without affecting the merits of this invention, such as passing the cable 7 entirely through the length of the pin and anchoring it in position at the lower end in the old and common manner.

As above described, one end of the cable 7 is fastened securely to the eye 8 as disclosed in Figures 2 and 3, the other end of the cable 7 65 is secured by some suitable means to a pulley member 11, which is mounted and keyed upon a spindle element 12 rotatively supported in the upper part of the housing 1 as at 13 and 14. A tension leaf spring 15 is also mounted 70 upon the spindle 12 in such a manner that when the pin 5 is in lowered position, as disclosed in Figure 1, the spring 15 will be wound under tension around the spindle 12, as clearly disclosed in Figure 4. As a means 75 for accomplishing the desired result, one end of the leaf spring 15 may be mounted on a pin member 16 extending from the housing 1, the other end of the leaf spring 15 being securely fastened to the spindle 12 as at 17 80 in such a manner that when the pin is in raised position, as shown in Figure 2, the leaf spring 15 will be unwound and comparatively loose around the spindle.

It is apparent from the above description 120

that when the pin 5 is released from contact with the alley 6 it will snap upward into position within the housing 1, and in order to eliminate the possibility of the head of the pin striking the pulley 11, and other mechanism within the housing 1, it is preferred that a bumper 18 be provided made of any suitable material such as rubber, having an opening 19 therein through which the cable 7 may loosely and slidably extend. As a further aid in relieving the shock of impact between the pin and housing, bumper springs 20 are provided, arranged in such a manner that the bumper 18 will be attached thereto, one end of the bumper springs 20 being held in fixed relationship to the housing 1 by means of inwardly extending grooved portions 21 of the housing.

This invention provides a very efficient means for returning the pins to the housing after being released from contact with the alley by means of the striking of the balls or otherwise. The prime advantage over other means is that the need of a long spring is entirely eliminated, a cable of wire or otherwise taking the place of the ordinary spring. The power or force necessary for returning the pin to the housing is obtained from the potential energy of a leaf spring mounted upon the pulley spindle within the housing, thereby providing a means for raising the pins which will be positive in its action, relying wholly upon the very small leaf spring mounted on a spindle.

It will be understood that many changes and modifications may be made in the form of the improvement of the invention, within the scope of the following claims, without departing from the spirit of the invention.

What I claim is:

1. An attachment for bowling alleys comprising a housing having a chamber adapted to receive a bowling pin, a buffer plate having an orifice forming a partition within the housing, a spindle within the housing above the partition, means passing through said orifice from said spindle and connected to said pins, other means in said housing above said partition connected to said spindle for revolving said spindle when said pins are in an extended position.

2. An attachment for bowling alleys comprising a housing having a chamber adapted to receive a bowling pin, a spindle within said housing and supported thereby, means extending from said spindle and connected to said pin, spring means within said housing and connected to said spindle for revolving said spindle when said pin is in an extended position.

3. In a game having an alley, pins and housings for receiving the pins, a spindle rotatively mounted within the housing, a pulley having a leaf tension spring mounted on the spindle, a cable attached to the pin and

pulley for winding thereon when the spring is under tension and the pin released from the alley.

4. In a game having an alley, pins and housings for receiving the pins, a spindle rotatively mounted within the housing, a pulley having a leaf tension spring fixed on the spindle, a cable attached to the pin and pulley for winding thereon when the spring is under tension and the pin released from the alley, buffer means positioned within the housing between the pin and spindle.

5. In a game having an alley, pins and housings for receiving the pins, a spindle rotatively mounted within the housing, a pulley having a leaf tension spring fixed on the spindle, a cable attached to the pin and pulley for winding thereon when the spring is under tension and the pin released from the alley, a buffer positioned within the housing between the pin and spindle comprising a main body member and a plurality of auxiliary buffer springs.

In testimony whereof I affix my signature.

RICHARD LINN LLOYD.
